(57) **CLAIM**

The ornamental design for a bag, as shown and described.

DESCRIPTION

FIG. 1 is a top front perspective view of a bag showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of the bag of FIG. 1 shown in an expanded configuration;

FIG. 9 is a front view thereof in an expanded configuration;

FIG. 10 is a rear view thereof in an expanded configuration;

FIG. 11 is a left side view thereof in an expanded configuration;

FIG. 12 is a right side view thereof in an expanded configuration;

FIG. 13 is a top view thereof in an expanded configuration; and,

FIG. 14 is a bottom view thereof in an expanded configuration.

The broken lines in the figures show portions of the bag that form no part of the claimed design.

The hatched lines in the figures show shading and not surface ornamentation.

1 Claim, 14 Drawing Sheets
